UNITED STATES PATENT OFFICE.

FRANCIS JOSEPH SMITH, OF GARY, INDIANA.

SPRING.

Application filed April 2, 1925. Serial No. 20,210.

This invention relates to suspension springs for motor vehicles and the like constituting improvements in my co-pending application, Serial No. 680,260, filed December 12, 1923, 5 and which application has matured into United States Patent No. 1,577,767 and has for an object the promotion of a novel and improved spring of great flexibility and strength for the support of the weight of 10 vehicles and the compensation for shocks and vibrations incident to the travel over rough roads.

One of the objects of my invention is to provide a leaf spring of a plurality of superimposed connected leaves of varying length, 15 and what I term as a variable strength spring functioning as though it were always carrying a full load. It has been found that the great difficulty involved in suspension 20 spring design is due to the varying load and the unsprung weight. Both of these make intermittent calls for great strength. The variable strength spring hereinafter to be described is designed to compensate for the 25 stress and strain placed on the spring and affording the greatest flexibility at all times.

To enable others skilled in the art to fully comprehend the underlying features of my invention, that they embody the same in the 30 various modifications in structure and relation contemplated, drawings depicting a preferred form have been annexed as a part of this disclosure and in such drawings, similar reference characters denote corresponding 35 parts throughout all the views, of which,

Figure 1 is a view showing the application of my invention to the axle and frame of a motor vehicle.

Figure 2 is a view of the spring detached.

Figure 3 is a disassembled view.

Figure 4 is a sectional view through the spring showing 28 leaves.

Figure 5 is a view of a suspension spring constructed in accordance with my design, 45 for the front end of the chassis.

Figure 6 is a detached view.

Figure 7 is a disassembled view.

Figure 8 is a view showing the spring attached to a fixed and a movable point, 50 known as the Hotchkiss drive.

Figure 9 is a view showing the full elliptical type of spring on the front end of the chassis.

Figure 10 is a disassembled view.

55 Figure 11 is a view of a spring having a fixed and a movable end, and being some-

what less resilient than the type of spring shown by Figures 1 and 5.

Figure 12 is a similar view to that shown by Figure 11. 60

Figure 13 is a type of spring shown by Figure 11, when detached.

Figure 14 is a view showing the spring, as shown in Figure 13, disassembled.

Figure 15 is a semicantilever type of 65 spring showing a modified form of the invention, for the rear end of the chassis.

Figure 16 shows the spring of Figure 15 disassembled.

Figure 17 is a sectional view through the 70 spring shown by Figure 15.

Figure 18 is a semicantilever for the rear end of the chassis.

It is generally recognized that the stress and strain on any single spring is not generally distributed throughout its entire length but rather, is concentrated near a point of support, which may be considered on a vertical line drawn through the axle 5, 75

as shown by Figure 1, to which the spring is attached by the U-bolt 6 and the connecting strap 7, fastened by the nuts 8. This

application embodies the practice of obtaining a more even distribution of the strain throughout the entire length of the leaves. 80

It is based on the fact that although flexure of any spring constructed of a plurality of superimposed, arched leaves, regularly graduated, is concentrated near the point of support, this rule will cease to operate as soon 85

as the flexure reaches a point considered on a horizontal line drawn through the axle and the loaded ends, or in other words, on a line at right angles to the vertical. Thus, 90

if any group of superimposed, graduated, flat leaf springs carried the load at their ends, as for instance by the links 9, 10, which are pivoted as at 11, 12, to the chassis 13, the

flexure of the leaves would be substantially semi-circular and evenly distributed. Consequently, if the spring is designed for the 95

chassis so that at least one-half of the total flexure of the spring takes place after the horizontal is reached, I can increase the safe load on such a spring at least 50%. I construct the spring as shown by Figures 1 to 100

3 inclusive by providing a top connecting spring 14, terminating in the eyes 15 whereby the spring may be attached to the links

as shown and thus bear the entire weight 105

of the load, thus connected to the axle of the wheel by the U-bolt or strap 6 above referred 110

to. It will be observed that the spring 14 is flexed slightly in the reverse direction to the superimposed leaves 15, while certain of the leaves are connected to the spring 14 by the strap 16, the shorter or top leaves are connected by the strap 6. In Figure 4, I have shown the leaves 16 as consisting of no less than 28 superimposed leaves which give the most efficient result in a spring construction 10 of the above character.

In actual practice, the leaf 14 is made of $\frac{1}{4}$ inch spring steel. The superimposed leaves 15 are preferably constructed of $\frac{3}{2}$ inch spring steel. The top spring has the 15 strength of substantially 72 pound per inch of flexure whereas the superimposed leaves have a flexure of substantially 25 pounds per inch. As shown by Figure 2, the top and superimposed leaves are under a strain of substantially 500 pounds. 20

In Figure 5 is shown a front spring. One end of the spring is preferably connected to a fixed pivot 18 of the chassis 13 whereas the opposite end 19 of the spring is connected to a movable or pivoted link 20 suspended as at 21. The spring proper is connected by the U-bolt or strap 22 to the I beam 23 of the chassis. The top main leaf 17 is therefore to be regarded as the reverse 25 stress or strength. The dead weight of the chassis is supported by the superimposed leaves, which are as flexible a group as is practicable. 30

In Figure 8 of the drawing the superimposed leaves 25 and the main top leaf 26 are similarly connected by the U-shaped strap 27 encircling the axle and connected at the top by the plate and the nut, used in the same manner above described. The main 35 leaf also terminates in eyes connected to a movable link 28 and a fixed support 29 and I have found that a spring of this type produces a forward thrust in the car wheel, whereas a decrease or flexure in the superimposed leaves and the top connecting leaf produces a backward thrust. From the 40 spring constructions in present use, a thrust is produced in opposite direction. 45

In Figure 9, I have shown the principle 50 of the variable strength spring applied to a full elliptical spring in which the intermediate main leaves 30, 31, are connected to the superimposed leaves 32 at the top and the superimposed leaves 33 at the bottom. In 55 this form of spring, the central leaves 30, 31, are under no strain when connected to the chassis of the vehicle and the front axle as shown by Figure 9 of the drawings.

In Figure 11, I have shown the spring 60 consisting of the superimposed leaves connected to the axle, the ends of the main leaves connected to a fixed pivot 34 and the pivoted link 35. This construction also permits of a horizontal thrust whereas in Figure 13, one end of the spring is connected

to the end 36 of the chassis and the opposite end to the link 37 attached to the chassis.

In Figures 13 and 14, I have shown the spring assembled and disassembled, there being provided a central main leaf 38, the top leaf 39, slightly bowed or flexed in the direction of the superimposed leaves 40. The leaf 38 terminates in the eyes 41. It will be observed that the superimposed leaves 40 and the short leaf 39 are connected 75 by the straps 42 so that they are disposed in substantial parallelism with the central leaf 38.

In Figures 15 to 18 inclusive, I have shown a modified form of the invention 80 where the spring is connected to the chassis 43 and the axle 44 of the vehicle, the superimposed leaves 45 being of decreased length and connected to the bottom main leaf 46 by the straps 47 and U-bolt 48. In Figure 18, the same type of spring is connected to the I beam 49 of the chassis, being shown, applied to the front wheel of the motor vehicle. As in the previously described form 85 of the invention, the bottom leaf 46 is of greater strength than the superimposed leaves.

It will be noted throughout all the drawings that show the different methods of attaching the springs to the chassis, that all 90 increases in the amount of flexure shown, will produce a slight forward thrust of the wheel along a horizontal plane and that all decreases in the amount of flexure shown, will produce a slight backward thrust along 95 a horizontal plane. All methods of spring design and attachment in use today, produce horizontal thrusts in the opposite directions. 100

The drawings also show that all of the 105 main leaves are shaped exactly the same after attachment to the vehicle, as they were before assembly. Thus, leaf 14 in Figure 3 has the same shape in Figure 1; leaf 17 in Figure 7 has the same shape in Figure 5; leaves 30 and 31 in Figure 9 have the same shape in Figure 10; leaf 39 in Figure 14 has the same shape in Figure 11; leaf 46 in Figure 16 has the same shape in Figure 15. Therefore, in these instances, the load represented by the empty vehicle is being supported entirely by the groups of light leaves, 110 which are as flexible as it is practicable to build. The whole group of leaves 15 in Figure 3, supports only 25 pounds per inch of flexure, being made of $\frac{3}{2}$ inch spring steel. While the leaf 14 of Figure 3 supports 72 pounds per inch of flexure, being made of $\frac{1}{4}$ inch spring steel. The shape that the 115 heavy leaf is given is governed in each instance, by the shape that the group of light leaves alone, is going to assume when the weight of the empty vehicle is applied to it. 120

The universal practice of arching the 125 leaves of a spring, causes the strain result-

ing from load to be concentrated within about one third of their length. Whereas, if any group of graduated leaves be left flat, the flexure resulting from load will be evenly distributed and circular. A spring in which the strain is evenly distributed, will safely carry 100% more weight than one made of well arched leaves. Figures 15, 16 and 18 show a design using principally flat leaves.

Throughout this specification, the endeavor has been to describe a laminated spring constructed of very light material arranged in cooperation with a small amount of very heavy material, so that a strain relation will exist between the two materials, that will always force the light material to be strained beyond a certain point before the heavy material can begin to be strained at all, in that given direction. The certain point of strain in the light leaves, being about equal to the strain that would be produced in the light leaves alone, by the application to the light leaves alone, of a weight about equal to the sprung weight of the vehicle.

While I have illustrated and described my invention with some degree of particularity, I realize that in practice various alterations therein may be made. I therefore reserve the right and privilege of changing the form of the details of construction, or otherwise altering the arrangement of the correlated parts, without departing from the spirit of the invention or the scope of the appended claims.

Having shown and described my inven-

tion, what I claim as new and desire to secure by United States Letters Patent is:—

1. A suspension spring comprising a main leaf of substantially heavy material, and a graduated group of leaves of light material, the said heavy main leaf being given the same shape as would be assumed by the group of light leaves after they alone had been placed under a weight substantially equal to the sprung weight of the vehicle for which it is designed, and means for assembling these leaves in cooperation with each other.

2. A suspension spring comprising a group of light leaves, a heavy main leaf maintained in a position of freedom from all strain resulting from the dead weight of the vehicle by said group of light leaves graduated in length, the said group of light leaves having been urged past that point of flexure at which fibre strain begins to be evenly distributed throughout the length of all of the leaves by the dead weight of the vehicle itself.

3. A suspension spring comprising an arched main leaf terminating in eyes and adapted to be attached at its ends to the chassis of a vehicle, a plurality of superimposed leaves of gradually decreased length bowed outwardly and in the reverse direction to the main leaf, the strength of the main leaf being substantially greater than the superimposed leaves and means for connecting said main leaf and superimposed leaves.

In testimony whereof I affix my signature.

FRANCIS J. SMITH. [L. s.]
